The ornamental design for a multi-function power supply, as shown and described.

DESCRIPTION

FIG. 1 is a first perspective view of a multi-function power supply showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is a perspective view of another state of the multi-function power supply thereof;

FIG. 10 is a perspective view of another state of the multi-function power supply thereof;

FIG. 11 is an enlarged view of the selected portion 11 in FIG. 1; and,

FIG. 12 is an enlarged view of the selected portion 12 in FIG. 2.

The dash-dash broken lines depict portions of the multi-function power supply that form no part of the claimed design. The long dash-short dash broken lines in FIGS. 1, 2, 11 and 12 represents the bounds of the enlargement taken from FIGS. 1 and 2 and forms no part of the claimed design.
